CLAIM

The ornamental design for an ear plug, as shown and described.

DESCRIPTION

FIG. 1 is a perspective view of the ear plug showing a front side;

FIG. 2 is a side view ear plug shown in FIG. 1;

FIG. 3 is a top view of the ear plug shown in FIG. 1;

FIG. 4 is a bottom view of the ear plug shown in FIG. 1;

FIG. 5 is another side view of the ear plug shown in FIG. 1;

FIG. 6 is a rear view of the ear plug shown in FIG. 1; and,

FIG. 7 is a front view of ear plug shown in FIG. 1.

The broken line foam portion is shown for illustrative purposes and forms no part of the claimed design.
